[57] CLAIM

The ornamental design for a device tag for display of electrical devices, as shown and described.

DESCRIPTION

FIG. 1 is a perspective view of the tag showing our new design;

FIG. 2 is a front elevation of the tag of FIG. 1;

FIG. 3 is a side elevation of the tag of FIG. 1;

FIG. 4 is a rear elevation of the tag of FIG. 1; and,
FIG. 5 is a perspective view showing the tag of FIG. 1 in
cooperative orientation with respect to an electrical display
device.

The broken lines are shown for illustrative purposes only
and form no part of the claimed design.
